United States Patent Office

Des. 212,225
Patented Sept. 17, 1968

212,225

LAVATORY

E. Peter Robare, 701 Orchard Hill Drive,
Louisville, Ky. 40214

Filed Dec. 29, 1967, Ser. No. 9,972

Term of patent 14 years

(Cl. D23—58)

FIG. 3

The dominant features of my design reside in the portions shown in full lines.

What is claimed is:

The ornamental design for a lavatory, substantially as shown and described.

UNITED STATES PATENT OFFICE
CERTIFICATE OF CORRECTION

Design No. 212,225

September 17, 1968

E. Peter Robare

It is certified that error appears in the above identified patent and that said Letters Patent are hereby corrected as shown below:

In the grant, lines 1 to 3, "E. Peter Robare, of Louisville, Kentucky," should read -- E. Peter Robare, of Louisville, Kentucky, assignor to American Standard Inc., of New York, N. Y., a corporation of Delaware, --; line 13, "E. Peter Robare, his heirs" should read -- American Standard Inc., its successors --; in the heading to the printed specification, lines 3 and 4, E. Peter Robare, 701 Orchard Hill Drive, Louisville, Ky. 40214" should read -- E. Peter Robare, Louisville, Ky., assignor to American Standard Inc., New York, N. Y., a corporation of Delaware --.

Signed and sealed this 17th day of February 1970.
